UNITED STATES PATENT OFFICE.

EDWARD PASDERA, OF ST. PAUL, NEBRASKA.

WIRE SPLICER AND STRETCHER.

Application filed July 18, 1923. Serial No. 652,399.

To all whom it may concern:

Be it known that I, EDWARD PASDERA, a citizen of the United States, and a resident of St. Paul, in the county of Howard and State of Nebraska, have invented a new and Improved Wire Splicer and Stretcher, of which the following is a full, clear, and exact description.

This invention relates to improved wire 10 splicing and stretching devices and particularly to a construction which may be readily operated for either stretching a wire in the usual sense when first installing the same or for stretching the wire and holding 15 the same in place during the connection of two ends.

Another object of the invention is to provide a splicing and stretching device which is particularly adapted for stretching and holding barbed wire.

A further object of the invention is to provide a device which when acting as a wire stretching device, may use any form of abutment and when acting as a splicer may dispense with abutments and act to draw the 25 two ends to an overlapped position whereby they may be manually connected together.

In the accompanying drawing—

Figure 1 is a side view of a device embodying the invention, the same being shown in operation preparatory to splicing a broken barbed wire.

Figure 2 is a side view of a device embodying the invention as it will appear when used in stretching the barbed wire.

Figure 3 is a perspective view on an enlarged scale, showing the various parts of the device.

Referring to the accompanying drawing 40 by numerals, the device is provided with a handle 1 made up of flat bars 2 and 3 held together by any suitable means, as for instance, rivets 4 and 5. These bars are bent at 6 and 7 respectively to form a bifurcated 45 upper end, the respective prongs 8 and 9 thereof having notches 10 and 11 formed therein. A spacing block 12 is arranged intermediate the ends of the prongs 8 and 9, said block being held in place by a bolt 50 or rivet 13. A bolt or rivet 14 acts as a pivotal member for the pull rod or pull hook 15 having a turned over hook end 16 formed with a slot 17 whereby it may readily straddle a wire. The slot 17 is, however, 55 preferably merely wide enough to readily

receive the wire and not permit the barb to pass therethrough whereby a barb may be engaged as shown in Figure 1 and the wire pulled to cause the broken ends to be overlapped preparatory to being spliced 60 manually.

When the device is used as a splicer, the section 18 of the wire is provided with a loop 19 which is fitted into the notches 10 and 11 and then the hook end 16 is caused to interlock with one of the barbs of the section 20. The handle 1 is then moved in the direction of the arrow 21 until the loose end 22 overlaps the loop 19 after which it may be manually moved through 70 said loop and then back and twisted so that it will not move out of the loop 19. The device may then be disconnected as the splicing operation is completed.

In case it should be desired to use the 75 device merely for stretching or bringing under tension a barbed wire, the hook 16 is interlocked with one of the barbs of the wire as shown in Figure 2 and the prongs 8 and 9 pressed against a suitable abutment, 80 as for instance, the post 23. The handle 1 may then be pulled for any desired extent and a suitable staple applied to posts 23 for securing the wire 24 thereto.

What I claim is:—

1. A combined wire splicer and stretcher, comprising a handle formed with a bifurcated end, each prong of said bifurcated end being formed with a notch, said notches aligning, means for holding said prongs spaced apart, and a hook member having a bifurcated end pivotally connected with said prongs near the ends where they join the handle.

2. A wire splicer and stretcher, comprising a body formed from a pair of metallic bars rigidly secured together, said bars at one end being spaced apart, means for holding said bars spaced apart, at one end for presenting a bifurcated structure, said bifurcated structure being formed with a notch near one end adapted to receive the loop of a wire to be pulled, and a bifurcated hook member extending into said bifurcated end, and means for pivotally connecting said hook member to said bifurcated end, part of the hook member facing said notches.

EDWARD PASDERA.
